UNITED STATES PATENT OFFICE.

FREDERICK HAINSWORTH, OF CHICAGO, ILLINOIS.

SNOW-PLOW ATTACHMENT TO LOCOMOTIVES.

SPECIFICATION forming part of Letters Patent No. 294,383, dated March 4, 1884.

Application filed March 12, 1883. (No model.)

To all whom it may concern:

Be it known that I, FREDERICK HAINSWORTH, a citizen of the United States, residing at the city of Chicago, in the State of Illinois, have invented certain new and useful Improvements in Snow-Plow Attachments to Locomotives, of which the following is a specification.

The nature and object of this invention are to provide an attachment to locomotives, worked by a rotary engine independent of the speed of the locomotive, to clear the track from snow.

Figure 1 is a longitudinal view of a locomotive, showing my snow-plow attachment. Fig. 2 is a front end view, with portions of cow-catcher cut away to clearly show the front twisted-shaped fan-wheels and knives.

This device can be attached to any locomotive.

A is a rotary engine attached to the boiler and to the frame of the locomotive by suitable means and stays, as at h, and located at the side of the locomotive, in advance of the drive-wheels, and fed by steam from the boiler through the pipe a.

D D is a shaft passing through the rotary engine A, and serving as its axis, placed alongside of boiler, and working in suitable bearings attached to the frame and boiler.

At the front and rear ends of the shaft D D are placed twisted or screw-bladed fan-wheels B B, and a little in advance of the front fan-wheels are attached the revolving knives C C. These twisted or screw-bladed fan-wheels work sufficiently close to the rails so that in revolving they clear the snow from the tracks. (See Fig. 2.)

e e is the valve-rod working the valve b in steam-pipe a, and extending to the cab at f, where it is worked by engineer.

i is the discharge-cock in the rotary engine, for the discharge of water from the cylinder.

d is the exhaust-pipe leading from the rotary engine to the smoke-stack.

g is a bracket attached to the boiler, and holds the rear end of the shaft D. It will be observed that there are two of these shafts located at each side of the locomotive and each 50 propelled by a rotary engine, and also each

has twisted or screw shaped fan-wheels and revolving knives.

The knives C C serve the purpose of chopping or cutting the snow when baked or packed, which enables the revolving wheels to readily remove it. The edges of the wings or fans or blades of the screw-bladed wheels are made sharp, so as to cut or loosen the snow. They are turned or twisted, so as to be parallel in their face to the rail, so that in revolving they will throw the snow to each side of the track.

It will be observed that the shaft D D is worked and operated by power derived from the locomotive-boiler; but the speed of the 65 rotary engine and the revolving velocity of the shafts in no way depend upon the speed of the locomotive. The rotary engines A are used only to give motion to the shafts D D and to the fan-wheels B B. Consequently the 70 speed of these twisted-shaped fan-wheels can be carried to any degree required, and thus the train can be moved slowly, while the fan-wheels B B can be revolved at a very high speed. This independent movement of the 75 fan-wheels will enable them to remove all the snow on the track, and thus the danger of disabling the locomotive and injuring the train entirely disappears.

I am aware that screw-bladed wheels have 80 been shown in conjunction with snow-plows; but the arrangement and combination with a locomotive, as herein shown, is believed to be new.

I claim—

1. The rotary engine A and revolving shafts D D, arranged alongside of boiler, provided with twisted-shaped fan-wheels B B, in combination with a locomotive, as and for the purpose shown.

2. The rotary engine A, revolving shafts D D, arranged alongside of locomotive-boiler, the twisted-shaped fan-wheels B B, and knives C C, in combination with a locomotive, as and for the purpose shown.

FREDERICK HAINSWORTH.
